SUCTION COLLECTOR FOR WASTE IN INDUSTRIAL PLANTS

Pierre Dauge, Laethem St. Martin, Belgium

Application September 29, 1955, Serial No. 38,150

Term of patent 14 years

(Cl. D9—2)

Fig. 1

Fig. 3

Fig. 2

Fig. 1 is a front elevational view of a suction collector for waste in industrial plants embodying my new design.

Fig. 2 is a top plan view thereof.

Fig. 3 is a side elevational view thereof.

It is to be understood that the material partially shown in Fig. 3, continues throughout the several wall panel areas as in Fig. 1.

I claim:

The ornamental design for a suction collector for waste in industrial plants, as shown.
